[57] ABSTRACT

This specification discloses a surface operated single tube pump intended for the raising of oil from the bottom of deep wells, including a small diameter well casing. The pump, considered in its entirety, comprises an air motor located at the ground surface, a tube of a diameter less than that of the well casing, the upper end of which is connected to the air motor, and a bottom pumping unit which is immersed in the oil at the bottom of the well and which comprises a piston slideable in the lower end of a cylinder, a tubular plunger having its upper end connected to said piston with a one-way check valve in the piston controlling the flow of liquid from the plunger through the piston, a spring abutment extending into the bore of the tube below the piston and an expansion coil spring between said abutment and the piston, and a one-way check valve mounted on the lower end of the cylinder for controlling flow of oil from the reservoir into the tube. A valve for bleeding air is mounted on the lower end of the tubular plunger.

SURFACE OPERATED SINGLE TUBE PUMP

The present invention relates to deep well pumps which are operated from the surface, and is concerned primarily with a pump of this type which includes a bottom of well pumping unit which is operated by pressure of the liquid being pumped which is generated in a single tube that extends from an air motor at the surface to the bottom of the well unit and which tube also performs the function of conducting the liquid being pumped to the surface.

BACKGROUND OF THE INVENTION

At the present time, deep well pumps of the general nature with which the present invention is concerned are well known. Such pumps ordinarily include a pumping unit which is located at the bottom of the well and a motor or comparable actuating device at the surface which operates the pump. In most of these known devices, at least two tubes in addition to the well casing are required. One of these tubes delivers liquid under pressure to the pumping unit for actuation thereof, while the liquid being pumped is raised in the other tube. The necessity for two tubes is an obvious disadvantage because it requires a well casing having a bore of sufficient diameter to accommodate the tubes.

In most of the pumping units which are installed at the bottom of the well, a piston is reciprocally mounted in a cylinder and is moved in both directions by a pressure medium. This results in a complex pumping mechanism.

OBJECTS OF THE INVENTION

With the foregoing conditions in mind, the present invention has in view the following objectives:

1. To provide a surface operated deep well pump which includes as characteristic and essential elements a bottom of well pumping unit which is mounted on the lower end of a small diameter tube which extends upwardly through a small diameter well casing to a motor at the top which generates pressure on the liquid in the tube to operate the pump and which tube also conveys the liquid being pumped to the surface.
2. To provide, in a pump of the character aforesaid, a bottom of well pumping unit which includes a piston reciprocal in the lower end portion of a cylinder a small diameter plunger depending from the piston and spring means for moving the piston upwardly when pressure on the liquid in the tube is relieved.
3. To provide, in a pump of the type noted, a bottom of well unit which includes a one-way check valve for controlling the flow of liquid from the tubular plunger through the piston and into the tube.
4. To provide, in the pump of the character described, a one-way check valve which is mounted on the lower end of a cylinder and which controls the flow of liquid from the reservoir at the bottom of the well into the cylinder.
5. To provide, in a pump of the character aforesaid, an air bleed which is mounted on the lower end of the tubular plunger.
6. To provide, in a pump of the type noted, a new and improved air motor which is located at the ground surface and which is effective to create pressure on the liquid in the tube and which also controls the upward flow of the liquid being pumped.

Various other more detailed objects and advantages of the invention such as arise in connection with carrying out the above ideas in a practical embodiment will, in part, become apparent, and, in part, be hereafter stated as the description of the invention proceeds.

SUMMARY OF THE INVENTION

The foregoing objects are achieved by providing a surface operated single tube pump which is particularly designed for use with wells having casings of small diameter, as for example in the order of two inches. The pump comprises an air motor at the ground surface including a power cylinder having a reservoir for the liquid being pumped mounted thereon and communicating with the bore of the cylinder by way of a lateral port therein. Mounted in this cylinder is a power piston which on alternate strokes opens and closes the port.

- 20 A tube of a diameter which permits of its insertion in the well casing has one end connected to the power cylinder. Mounted on the lower end of this tube is a bottom of well pumping unit comprising a piston reciprocal in a cylinder, a tubular plunger of a diameter smaller than that of the piston having its upper end connected to the piston with a one-way check valve in the piston controlling flow of the liquid from the plunger into the tube. Extending into the bore of the tube below the piston is an abutment. An expansion coil spring is interposed between the abutment and the piston and is effective after being compressed by downward movement of the piston under the influence of pressure of liquid in the tube to move the piston upwardly when this pressure is relieved. Mounted on the lower end of the cylinder which is immersed in the oil reservoir at the bottom of the well is a one-way check valve which controls the flow of oil from the reservoir into the tube. An air bleed valve is also mounted on the lower end of the tubular plunger.

For a full and more complete understanding of the invention, reference may be had to the following description and the accompanying drawings wherein:

FIG. 1 is a side view showing the ground in section, a well casing broken away, an air motor at the ground surface and a bottom of well pumping unit diagrammatically;

FIG. 2 is a perspective illustrating the air motor in section;

FIG. 3 is a detailed section on an enlarged scale illustrating one position of a valve in the air motor;

FIG. 4 is a detailed section similar to FIG. 3, depicting another position of the valve in the air motor piston;

FIG. 5 is a perspective of the bottom of well pumping unit as shown in section;

FIG. 6 is a detailed section on an enlarged scale of the check valve assembly at the upper end of the tubular plunger of the unit of FIG. 5;

FIG. 7 is an enlarged detailed section of the check valve assembly at the bottom of the pump cylinder;

FIG. 8 is a perspective illustrating the elements of the bleed valve in exploded relation;

FIG. 9 is a perspective of a modification illustrating a mechanical device for reciprocating the power piston in the power cylinder.

DESCRIPTION OF THE PREFERRED
EMBODIMENT

Referring now to the drawings, wherein like reference characters denote corresponding parts, and first more particularly to FIG. 1, a piece of ground is designated 10 and presents an upper or ground surface 11. It includes a lower portion over oil sands 12 in which an oil reservoir 13 is formed. Extending between reservoir 13 and ground surface 11 is a well casing 14 which is of small diameter as compared to such casings heretofore employed having a bore with a diameter in the order of two inches. Mounted on ground surface 11 over the upper end of well casing 14 is an air motor identified in its entirety at 15. Extending through well casing 14 is a tube 16 which ordinarily will have the property of flexibility to the degree which permits it to be wound on a drum. Mounted on the lower end of tube 16 is a bottom of well pumping unit designated generally 17 and which is illustrated in FIG. 5.

Referring now to FIG. 2, a power cylinder is designated 18. One end of cylinder 18 is provided with a flange 19 which is used in attaching the upper end of tube 16 thereto. Cylinder 18 is formed with a lateral port 20 and mounted on cylinder 18 is a reservoir 21 which receives and contains the oil being pumped. Port 20 communicates with bore 22 of cylinder 18 and reservoir 21. Mounted on the other end of power cylinder 18 is a disc-like plate 23. A power piston 24 is reciprocal in bore 22, with a seal 25 being provided where piston 24 passes through an opening in plate 23. Power cylinder 18 is also provided with a bleed port 26.

Mounted on plate 23 is a motor cylinder 27, and on the outer end of the latter is a circular head 28. Bolts 29 extend between plate 23 and head 28 and maintain the assembled relation of cylinder 27 therebetween.

An air piston 30 reciprocates in cylinder 27 with rings 31 providing a seal therebetween. Piston 30 is mounted on a piston rod 32 which passes through an opening 33 in head 28 and its outer end is received in a positioning tube 34, the function of which will be later described. Head 28 is provided with an air inlet opening 35 which communicates with a fitting 36 to which an air tube 37 is connected. Air tube 37 is connected to an appropriate source of air under pressure, such as a compressor.

Referring now more particularly to FIG. 3, piston 30 is shown as having opposed faces 38 and 39. Extending between faces 38 and 39 is a passage 40 of circular cross-section with a counterbore 41 at the face 38 and a second counterbore 42 at the face 39.

As shown more clearly in FIG. 2, piston rod 32 has a longitudinal bore 43 which is opened at the outer end of the piston rod and which terminates at its inner end in a lateral passage 44 which opens onto passage 40.

A sliding valve is referred to in its entirety by the reference character 45, as depicted in FIGS. 3 and 4. It is of spool shape, presenting a central cylindrical main body portion 46 and end flanges 47 and 48. Body portion 46 is formed with an annular groove 49, the bottom of which is formed with openings 50 which communicate with a bore 51 of said body portion 46 in one position of the valve as shown in FIG. 3. Bore 51 is enlarged at each end to provide counterbores 52 and 53. An expansion coil spring 54 is received in counterbore 52, and another expansion coil spring 55 in counterbore 53.

Opening onto face 39 is an arm 56 of an elbow passage, the other arm 57 of which communicates with bore 51 by way of groove 49, in the position depicted in FIG. 4, which shows the valve 45 as shifted to the right, speaking with reference to the showing of the drawing.

Referring now to FIG. 3, a spring abutment 58 is shown as mounted on the innerface of plate 23 by a screw 59 which may be rotated to adjust the position 10 of abutment 58 relative to plate 23. The outer end of spring 54 is adapted to engage abutment 58 as the valve 45 approaches its limit of movement in the direction of plate 23. In order for this to take place, it is necessary 15 that piston 30 be in the angular position which will cause the end of spring 54 to engage abutment 58. To insure of this, that portion of piston rod 32 which is received in tube 34 carries a pin 60 which slides in a groove 61 (FIG. 2). Thus, relative rotation of piston 30 and cylinder 27 is inhibited.

20 In describing the operation of air motor 15, the space between piston 30 and plate 23 will be referred to as 62 and the space between piston 30 and head 28 as 63. With the valve 45 in the position depicted in FIGS. 2 and 3, air under pressure enters the inlet 35 and is effective 25 on face 39 of piston 30. In this position, communication through the elbow passages 56 and 57 is prevented because the main body portion 46 of valve 45 closes the inner end of elbow arm 47. However, in this same position, the inner end of lateral passage 44 communicates 30 through groove 49 and openings 50 to the space 62. Thus, pressure of air in space 63 moves piston 30 towards plate 23, reducing the size of space 62. This occurs because air from space 62 is exhausted 35 through counterbore 52, bore 51, openings 50, groove 49, lateral passage 44 and bore 43 to the exterior of the cylinder. During this movement, power piston 24 is first moved to close port 20 and then apply pressure to the oil in tube 16.

40 When the outer end of spring 54 engages abutment 58, valve 45 is shifted from the position shown in 53 to that depicted in FIG. 4. In the latter position, the so-called exhaust passage 44 is closed by the body portion 46 of valve 45 and the arm 57 of the elbow passage is open. Thus, air passes from the space 63 to the space 62 and the pressures on the piston faces 38 and 39 are equalized or balanced. However, as the face 38 is of greater area than the face 39, the total pressure of air in space 62 on face 38 is greater than the total pressure on face 39 and the piston 30 is moved towards the head 28 until spring 55 engages head 28 to cause a shifting of the valve back into the positions of FIG. 2 and 3. During this so-called return stroke, power piston 24 is moved past the port 20 to open the latter and permit oil to flow from the tube 16 into the reservoir 21 under the influence of the bottom of the well pumping unit 17.

Referring now to FIG. 5, the bottom of well pumping unit 17 is shown as mounted on the lower end of the tube 16. This unit includes a pump cylinder 6, which has a bore 64. Slidable in bore 64 is a pump piston 65 having a threaded socket 66 at one end which receives a fitting 67 formed with a central passage 68. The other or lower end of piston 65 is formed with another threaded socket 69 which receives a fitting 70 that anchors the upper end of a tubular plunger 71 to piston 65.

Opening onto socket 66 is a valve chamber 72 terminating at its lower end in a tapered seat. A ball valve 73 is loosely received in chamber 72 and is movable into open position by upward pressure of oil from plunger 71. Fitting 67 is formed at its lower end with two radial grooves 74 which communicate between chamber 72 and passage 68 where ball 83 is its uppermost position engaging the lower end of fitting 67.

Ball valve 73 and the structure associated therewith constitutes a one-way check valve. Under many conditions one such check valve at the upper end of plunger 71 will be satisfactory. However, to assure of better results, two such check valves are provided at this point. Thus, piston 65 has an inwardly extending flange 75 defining a restricted bore 76 which opens onto the tapered bottom of chamber 72 at its upper end and onto a lower valve chamber 77 terminating in a conical seat, the lower end of which communicates with a passage 78 in fitting 70. Tubular plunger 71 communicates with passage 78.

Piston 65 is formed with a pair of radial grooves 79 which open onto chamber 77 with their inner ends opening onto bore 76. Thus, when a second ball valve 80 is moved upwardly by fluid pressure into engagement with flange 75, oil will flow from chamber 77 into bore 76.

A packing 81 is interposed between fitting 70 and pump cylinder 6 below piston 65 and moves with the piston. A spring abutment 82 extends inwardly from pump cylinder 6 and is engaged by the lower end of an expansion coil spring 83. The upper end of spring 83 engages packing 81 and serves a dual function. Its main purpose is to move piston 65 and plunger 71 upwardly after it has been compressed, but it also performs the auxiliary function of tending to expand packing 81 against the inner surface of pump cylinder 6.

While only a single spring 83 is disclosed in FIG. 5, it will be understood that additional springs may be provided in alignment along pump cylinder 6 to provide a required degree of force.

A cylinder member 9 has externally threaded end portions separated by an annular flange 8. One of these end portions is screwed into the lower end of pump cylinder 6, while the other end portion is threaded into the upper end of pump closure 7.

Formed on pump closure 7 at its lower end is an upwardly projecting annulus 84 presenting a restricted passage 85. Below annulus 84, closure 7 is internally threaded at 86 to provide means for attaching a screen or filter thereto. Passage 85 opens onto a valve chamber 5, the lower end of which is conical. Chamber 5 terminates at an annular shoulder 87 formed with two radial grooves 88. A plug 89 is fitted in a socket 90 in the lower end of closure 7 and cooperates with chamber 86 in loosely confining a ball valve 90 to provide a one-way check valve.

While a single check valve for controlling the flow of oil from the underground reservoir into the lower end of closure 7 might be adequate under many conditions, a double check valve at this site is disclosed. Thus, plug 89 has a restricted bore 91 extending from the lower face of plug 89 to a conical seat formed as the lower end of a valve chamber 92. The upper face of plug 89 is formed with a pair of radial grooves 93. Plug 89 is secured in position by a cup-shaped nut 94 having a central passage 95. An upper ball valve 96 is loosely held in chamber 92 by nut 94.

The wall defining tubular plunger 71 is externally threaded. Screwed onto end portion 97 is a sleeve 98 which is slidably received in the upper extension of member 9. The lower end of sleeve 98 carries an end wall formed with a central opening in cooperating relation to the upper end of passage 95 and terminating at a valve member receiving a ball valve 99.

A valve block 100 is interposed between the end wall of sleeve 98 and the end portion 97 of plunger 71. Block 100 is also formed with a valve chamber which receives another ball valve 101. Ball valves 99 and 101, together with the chambers in which they are received, constitute a bleed valve assembly which rids the interior of plunger 71 of air.

OPERATION

The pump is first primed by filling tube 16 with oil. This may be accompanied by withdrawing power piston 24 to leave port 20 open and introducing as much oil as is required into reservoir 21. On its power stroke, piston 24 first closes port 20 and then builds up pressure on the oil in tube 16.

This pressure is effective on the upper end of piston 65 of the bottom of well unit 17 to move piston 65 downwardly. This movement causes oil which has collected in the lower end of tube 16 to enter plunger 71 past the bleed valves at the lower end thereof. At the same time, spring 83 is compressed. Oil in plunger 71 will be under pressure as the latter moves downwardly to open valves 73 and 80 and admit oil to the upper side of piston 65.

It is noted that the cross-sectional area of passage 68 is much less than the area on the underside of piston 65 on which the pressure of liquid below piston 65 is effective. This underside piston surface comprises the shoulder at the lower end of the head of plunger 71 and the lower surface of packing 81. With downward pressure applied to the column of liquid in pump cylinder 6, piston 65 is moved downwardly to build up pressure on the liquid below piston 65. This liquid enters bore 78 of plunger 71 and is forced upwardly past check valves 80 and 73 and through the passage 68 to the upper side of piston 65 where it joins the column of liquid in bore 64. To insure that this action takes place, the difference in the exposed cross-sectional areas of the upper and lower surfaces of check valve 73 cannot be greater than the difference of the lower effective areas of pistons 65 and 98.

When piston 24 makes its return stroke, pressure on the column of oil in tube 16 is relieved and port 20 opens. Spring 83 is now effective to move pump piston 65 upwardly which imparts upward movement to the column of oil because any tendency of this oil to flow back past the valves 73 and 80 is prevented because such a tendency closes these valves.

Upward movement of piston 65 also creates a vacuum condition in pump cylinder 6 below the piston. This condition causes oil to flow into the space above closure 7 from sands 12 because valves 90 and 96 will move to open position to permit such flow. They are moved to closed position on downward movement of piston 65.

THE MODIFICATION

While the air motor 15 is believed to be the preferred device for reciprocating power piston 24, it is possible to use a purely mechanical device for this purpose.

FIG. 9 illustrates such a device in its simplest form. Thus, a lever 102 is pivoted at 103 on a support 104 and one end is pivotally connected at 105 to a push-pull rod 106, which is, in turn, connected to one end of power piston 24.

While preferred specific embodiments are herein disclosed, it is to be clearly understood that the invention is not to be limited to the exact constructions, mechanisms and devices illustrated and described because various modifications of these details may be provided in putting the invention into practice.

What is claimed is:

1. In a surface operated deep well pump intended for use with a well casing of small diameter:
  - a. a power cylinder having a bore at said surface;
  - b. a power piston reciprocal in said bore;
  - c. means for reciprocating said power piston;
  - d. a reservoir at said surface and connecting with a port in said power cylinder;
  - e. a tube of a diameter less than that of said casing and received therein, said tube being connected at one end to said power cylinder and extending substantially to the bottom of said casing, and
  - f. a bottom of well pumping unit mounted on the other end of said tube, said unit comprising:
    - i. a pump cylinder connecting with said tube;
    - ii. a pump piston reciprocal in said pump cylinder,

5

- iii. a tubular plunger having upper and lower ends, with the upper end fixedly secured to said pump piston and said plunger depending from said pump piston,
- iv. a one-way check valve in said pump piston controlling the flow of liquid through said pump piston and permitting flow of liquid from said plunger through said pump piston,
- v. an inwardly extending abutment in said pump cylinder,
- vi. a compression spring interposed between said pump piston and said abutment,
- vii. a sleeve fixedly secured to the lower end of said plunger, in sliding engagement with an inner surface of said pump cylinder and constituting a seal closing off the lower end of the space between said pump cylinder and said plunger,
- viii. a check valve at the lower end of said pump cylinder and spaced from the lower end of said plunger controlling the flow of liquid thereinto, and
- ix. an air bleed at the lower end of said plunger in the form of a one-way check valve.

2. The surface operated deep well pump of claim 1 in which the air bleed at the lower end of the plunger comprises a pair of aligned one-way check valves.
